UNITED STATES PATENT OFFICE.

GEORGE WASHINGTON GILMAN, OF JANEVILLE, WISCONSIN, ASSIGNOR TO AMERICAN METALS CO., OF JANEVILLE, WISCONSIN, A CORPORATION OF WISCONSIN.

PRICE MARKER.

Application filed July 5, 1922. Serial No. 572,791.

To all whom it may concern:

Be it known that I, GEORGE WASHINGTON GILMAN, a citizen of the United States, and a resident of Janesville, in the county of Rock and State of Wisconsin, have invented 5 a new and Improved Price Marker, of which the following is a full, clear, and exact description.

The present invention relates to new and 10 useful improvements in price markers, and it pertains more particularly to a price marker especially adapted for use in connection with pencils, fountain pens, and the like.

15 It is one of the objects of the invention to provide a price marker in which the marking element is so constructed that it depends upon the construction of the article with which it is used for its operation.

20 It is a further object of the invention to provide a price marker which may be removed after it has served its purpose, and used from time to time on various articles of a similar nature.

25 With the above and other objects in view, reference is had to the accompanying drawings, in which—

Figure 1 is a view in elevation of a pencil having a price marker thereon constructed 30 in accordance with the present invention;

Fig. 2 is a detail perspective view of the price marker shown attached to a pencil;

Fig. 3 is a detail view in elevation of a 35 fountain pen with a slightly modified form of price marker attached thereto;

Fig. 4 is a detail perspective view of the marker used in connection with the fountain pen and shown in Fig. 3.

Referring more particularly to the drawings the reference character 11 designates a pencil, and said pencil is of the type which has two spaced beads 12. The reference character 13 designates a band of resilient metal or other resilient material, and said band is of a width substantially equal to the space between the beads 12. This band 13 has a plurality of numerals 14 thereon to designate the price of the pencil when

the band is positioned thereon, it being understood that different bands may carry different price values as desired. 50

In use this form of the invention is adapted to be snapped about the pencil 11, between the beads 12, as shown in Fig. 1. When the pencil has been sold, the band is 55 expanded by spreading the ends 16 thereof and is removed from the pencil for future use.

In that form of the invention shown in Figs. 3 and 4, the reference character 17 designates a fountain pen, and 18 designates the price marker band. In this embodiment of the invention the band is provided near one of its ends with a projection or lug 20, and said projection or lug 20 is adapted to be received within one of the vent openings of the fountain pen cap in order that the band 18 may be retained against movement relative to the fountain pen cap. In lieu of one projection or lug 20, an additional 60 lug 23 may be employed if desired, depending upon the type of article with which the price marker band is adapted for use. 65

From the foregoing it is apparent that the present invention provides a new and 70 improved form of price marker for pencils, fountain pens, and the like, which will be securely retained in position upon the pencil or pen, and, at the same time, may be readily removed when the pencil or pen has been 75 sold, for subsequent use upon another article of this character.

What is claimed is:

In combination with a fountain pen, a portion of which is provided with air vent 80 holes, a price marker, said price marker comprising a band of resilient material 85 adapted to embrace the fountain pen, and an integral projection carried by said band of resilient material and adapted to be received within one of the air vent openings of the pen to prevent longitudinal movement of the price marker relative to the pen. 90

GEORGE WASHINGTON GILMAN.
